(57) **CLAIM**

The ornamental design for a television console, as shown and described.

DESCRIPTION

FIG. 1 is a front perspective view of a television console;
FIG. 2 is a front elevational view thereof;
FIG. 3 is a rear elevational view thereof;
FIG. 4 is a left elevational view thereof;
FIG. 5 is a right elevational view thereof;
FIG. 6 is a top plan view thereof; and,
FIG. 7 is a bottom view thereof.

The broken lines are shown for illustrative purposes only and form no part of the claimed invention.
